WILFORD W. DAKE, OF MUSKEGON, MICHIGAN, ASSIGNOR TO PYLE-NATIONAL ELECTRIC HEADLIGHT COMPANY, OF CHICAGO, ILLINOIS, A CORPORATION OF NEW JERSEY.

ELASTIC-FLUID TURBINE.

1,035,820.

Specification of Letters Patent. Patented Aug. 13, 1912.

Original application filed July 7, 1910; Serial No. 570,879. Divided and this application filed January 23, 1911. Serial No. 604,086.

To all whom it may concern:

Be it known that I, WILFORD W. DAKE, a citizen of the United States, residing at Muskegon, in the county of Muskegon and State of Michigan, have invented new and useful Improvements in Elastic-Fluid Turbine-Engines, of which the following is a specification.

My present invention relates to elastic fluid turbine engines and its object is to provide an improved elastic fluid valve and valve governor for such engines, etc., which shall be effective and simple in construction and operation. This object is attained by, and my present invention is embodied in, the mechanism hereinafter described, illustrated in the accompanying drawings, in which—

Figure 1 is a vertical section of such an engine to which my invention is applied, taken on the axial plane of the engine's rotor, certain parts being broken away; Fig. 2 is a sectional view of certain parts taken on line $s-s$ of Fig. 1; Fig. 3 is a transverse section of certain parts shown in Fig. 2 and taken on line $x-x$ thereof, and Fig. 4 is an under plan view of the rotor shaft and parts of the governor connected therewith.

A frame or casing 1 incloses the operative parts of the turbine engine to which my present invention is applied. The screw plug 2 may be removed to supply oil. The rotor shaft 3 carries the rotor body 4 provided with buckets 5. The elastic fluid (hereinafter referred to as steam) is conducted from its supply by a suitable passage, as the circular passage 6 in the casing, through an annular opening 7 and a passage 8 into the recess 9 formed in the inner face of the retaining nut 10. The steam 35 then passes through the strainer 11, and through the passage 13 therein, whose lower extremity forms the seat of the valve 14; it is thence discharged by suitable alining passages 15, as shown, into the rotor buckets 5. 40 The steam may also be supplied through the opening 45.

A governor to control the valve 14 and regulate the supply of steam to the buckets, comprises and is operated by the following 50 parts: when the centrifugal force becomes sufficient to overcome the spring 18, governor bell-crank levers 19 pivoted at 20 on the rotor body move the sleeve 21 along the rotor

shaft 3 (which said sleeve encircles) and, the end of such sleeve being joined to the 55 thrust collar 22 (bearing on the carbon washer 23 held in the non-rotating collar 24), moves said collar 24 axially the rotor shaft. This movement throws the lever 25, fulcrumed at 26 and pivoted at 27 to the collar 24, which movement, through the anti-friction roller 28, operates the lever 29 fulcrumed at 30, and thus closes the valve 14 against the pressure of its spring 31 surrounding the valve stem 32, by bearing 65 against the adjusting nut 33, which may be locked in proper adjustment by the jam nut 34. The pressure of the spring 18, one end of which is fastened to the sleeve 21 and the other to the collar 43, is adjusted by screws 70 35 threaded in such collar and journaled on the rotor body, such screws being held from accidental turning by their flat sided heads being held in engaging recesses 36 in the face of the rotor body. When the screws 35 75 are turned to adjust the pressure of spring 18, their flat sided heads are forced, by so turning the screws, to mount the inclined sides (shown in Fig. 4) of the recesses 36 at each half turn; the pressure of the spring 18 80 tending to keep the heads in the recesses and the turning of the screws raising the heads out of such recesses.

The support or cage 37 of the valve 14 is formed of separate piece from the casing or 85 frame of the engine, is conical in shape, as shown, and is adapted to tightly fit in a corresponding recess in such casing, in which it is securely held as by the retaining nut 10, but may be readily removed to effect repairs, 90 cleaning, etc. A passage 38 leads from passage 8 to the rear of the valve 14 for the purpose of admitting steam to balance the pressure of the steam on the face of the valve; the area of the cross-section of the 95 passage 13 and of the cross-section of the annular chamber 46 is, in order to effect a perfect balance, equal. The internal rib 39 in the casing serves to confine lubricating oil, as shown in the oil chamber 40; the 100 vapors in the casing chamber, stirred by the motion of the running parts of the engine, take up this oil and thus the governor, etc., are constantly lubricated. The screw plug 41 closes an opening in the casing through 105 which the screws 35 may be adjusted, and

the screw plug 42 may be removed to supply oil to the chamber 40. The exhaust pipe is shown at 44.

This application is division 3 of my original application Serial No. 570,879, filed July 7, 1910.

My invention may be embodied in varying mechanisms and may be applied to other types of elastic fluid engines, and I do not propose to confine myself to the construction shown and described.

I claim—

1. In a machine of the character described, a valve cage having a lifting valve and valve-seat therefor, a fluid supply passage controlled by the valve, and a fluid passage leading from the fluid supply to the inner side of the valve opposite the valve-seat, to balance or counteract the pressure of the fluid on the face of the valve.
2. In a machine of the character described, a valve support having a lifting valve and a seat therefor and a fluid supply passage leading to the valve seat and controlled by the valve, said support having also a fluid passage leading from the source of fluid supply to the inner side of the valve opposite the valve seat, the area of so much of the face of the valve as is pressed by the fluid supplied by the first-mentioned passage in the closed position of the valve being equal to the area of the rear of the valve pressed by the fluid supplied by the second mentioned passage.
3. In a machine of the character described, a conical and removable valve cage having a fluid strainer with a fluid passage and radially extending straining passages communicating therewith.
4. In a machine of the character described having a casing frame and a rotatable shaft and a valve for controlling its rotary speed, a governor for said valve comprising a governor lever centrifugally controlled, a second lever fulcrumed on the casing frame, means intermediate the governor lever and the second lever to actuate the latter by the former, and a third lever operating to close the valve and actuated by the second lever, said levers and actuating means being contained in the casing frame.

5. In a machine of the character described having a frame and a rotatable shaft and a valve having a valve stem, for controlling its rotary speed, said valve and stem having a longitudinal reciprocal movement, a governor for said valve comprising a governor lever centrifugally controlled, a sleeve encircling the shaft and slideable thereon by the governor lever, a second lever fulcrumed on the frame and having a collar pivoted thereto and adapted to be moved longitudinally the shaft by said sliding movement of the sleeve, and a third lever operating the valve stem to close the valve and actuated by the second lever.

6. In a machine of the character described having a frame and a rotatable shaft and a rotor carried thereby and a valve for controlling its rotary speed, a governor for said valve comprising a collar encircling the shaft, means intermediate the collar and the valve to control the latter by the movement of the former, a governor lever centrifugally controlled, a sleeve encircling the shaft and slideable thereon by the governor lever and adapted to move the collar, and a spring pressing against said movement and whose tension is adjustable by screws carried by the rotor and threaded in a collar carrying the spring.

7. In a machine of the character described, having a rotatable shaft and a rotor carried thereby and a valve for controlling its rotary speed and a governor for said valve comprising a governor lever centrifugally controlled and connections intermediate the governor lever and the valve to operate the latter by the movement of the former, a spring pressing against said movement whose tension is adjustable by screws carried by the rotor and threaded in a collar carrying the spring, and whose heads are held in engaging depressions against accidental movement.

In testimony whereof I have hereunto set my hand in presence of two subscribing witnesses.

WILFORD W. DAKE.
